SEPARABLE BUTTON

Jakob Hojnowski, Nekoosa, Wis.

Application August 13, 1937, Serial No. 158,984

3 Claims. (Cl. 24—100.5)

This invention relates to certain new and useful improvements in separable buttons.

The primary object of the invention is to provide a separable button formed of two separable sections comprising a head and base with a spring catch between the head and base when the separable sections are assembled.

A further object of the invention is to provide a separable button of the foregoing character wherein the spring catch between the head and base of the assembled button sections includes a resilient slidable element carried by the head of the button for interlocking engagement with a part of the base of the button.

A still further object of the invention is to provide a separable button wherein a spring latch connection between the head and base sections of the button includes a sliding spring comprising a pair of resilient legs for interlocking engagement with a spear head carried by the base section of the button.

It is a further object of the invention to provide a separable button wherein a slidably mounted spring pressed pin carried by the head section of the button is adapted to be engaged with an apertured spear head carried by the base section of the button for retaining the head and base sections in assembled relation.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a top plan view of a separable button constructed in accordance with the present invention;

Figure 2 is a bottom plan view;

Figure 3 is a horizontal sectional view taken on line 3—3 of Figure 4, showing the sliding spring catch between the head and base sections of the button with the spring catch illustrated by dotted lines as being slidably moved to permit separation of the button sections;

Figure 4 is a side elevational view of the button as shown in Figure 1;

Figure 5 is a cross-sectional view taken on line 5—5 of Figure 1;

Figure 6 is a cross-sectional view taken on line 6—6 of Figure 1;

Figure 7 is a top plan view of the bottom wall section of the head of the button showing the upset portions carried by said wall section for spacing the two wall sections of the button head

from each other to provide a clearance for the slidably mounted spring catch;

Figure 8 is a top plan view of another form of separable button;

Figure 9 is a bottom plan view of the button shown in Figure 8 with the slidably mounted spring pressed pin for retaining the buttons in assembled relation as shown by dotted lines in its retracted releasing position;

Figure 10 is a side elevational view of the button shown in Figure 8;

Figure 11 is a top plan view of the bottom wall section of the head of the button;

Figure 12 is a cross-sectional view taken on line 12—12 of Figure 8;

Figure 13 is a side elevational view of the bottom section of the separable button shown in Figure 8; and

Figure 14 shows side and top plan views of the sliding spring pressed pins forming the spring catch of the form of button shown in Figs. 8 to 13.

Referring more in detail to the accompanying drawing and particularly to Figs. 1 to 7, the separable button is formed of two main parts, comprising a head section 15 and a base section 16. The head and base sections 15 and 16 are separably connected together by spring latch devices.

The head section 15 comprises a top plate 17 of disk formation with a depending marginal flange 18 for engagement with the bottom disk plate 19 in a manner presently to appear, the central portion of the top plate 17 having an upstanding ornamental bulged portion 20 to provide clearance for a part of the spring latch connection between the separable button sections 15 and 16.

The bottom plate 19 of the head section 15 carries a series of circumferentially spaced upstanding bosses 21 engageable with the bottom face of the top plate 17 for spacing the bottom plate 19 from the top plate, the marginal flange 18 on the top plate being swaged into retaining engagement with the marginal edge of the bottom plate 19. A central opening 22 is formed in the bottom plate 19 and is surrounded by a depending relatively short tubular neck 23. For purposes presently to appear, a cam-shaped boss 24 rises from the bottom plate 19 in transverse alignment with one of the upset portions 21 and the marginal edge of the disk 19 outwardly of the cam 24 has a lug 25 struck up therefrom.

A spring catch is slidably carried by the head section 15 of the button and is slidably mounted thereon in the space afforded by the upstanding projections 21 on the bottom plate 19, the spring

catch being formed of a piece of resilient wire bent into U-shape and comprising side legs 26 connected at one end by the piece 27 that forms a finger grip. The side legs 26 of the spring catch 5 are crenelated to provide pin receiving loops 28, while the terminal ends of the side legs 26 are flared outwardly as at 29. The spring catch is positioned in the head section 15 to have the side legs 26 thereof straddle the cam boss 24 and 10 also the lug 25 while the marginal flange 18 upon the top plate 17 has a cut-away portion 30 as shown more clearly in Figs. 3 to 5 to permit outward sliding movement of the spring catch to the dotted line position shown in Figure 3, the cam boss 24 acting on crenelated portions of the side 15 legs 26 to separate the pin receiving loops 28.

The base section 16 of the separable button comprises a disk 31 carrying an upstanding tubular neck 32 for end abutting engagement with 20 the neck 23 depending from the bottom plate 19 of the head section 15 and said disk 31 of the base section has a pin 33 centrally rising therefrom and passing through the neck 32 to enter the neck 23 on the head section with the upper 25 end of the pin 33 received in the upwardly bulged portion 20 in the top wall 17 of the head section. As shown more clearly in Figs. 5 and 6, the upper end of the pin 33 is provided with an enlarged conical head 34 defining a shoulder 35 30 beneath which the loop portions 28 of the side legs 26 of the spring catch are adapted to be positioned for retaining the pin 33 against lowering movement and to retain the head and base sections 15 and 16 of the separable button in assembled relation.

In the form of invention illustrated in Figs. 8 to 14, the separable button comprises a head section 15a and a base section 16a separably connected thereto, the head section 15a comprising a top plate 17a and a bottom plate 19a connected together by the marginal flange 18a on the top plate engaged with the peripheral edge of the bottom plate 19a. The plate 19a as shown in Figure 11 has two pairs of diametrically opposite struck-up lugs 21a and two other pairs of diametrically struck-up lugs 24a, an abutment lug 25a being struck-up from the plate 19a at the outer ends of each pair of lugs 24a.

In lieu of the form of spring catch shown in Figures 1 to 6, comprising the U-shaped resilient wire, there is provided a tensioned sliding pin 26a carrying a rectangular frame 28a at one end thereof with a finger piece 27a depending from the outer end of the rectangular frame 28a. The sliding pin is mounted between the top and bottom plates 17a and 19a and incloses one of the upstanding lugs 25a, the sliding pin being selectively positioned at either side of the plate 19a and a coil spring 36 confined within the frame 28a engages at one end the end of the frame adjacent the pin 26a while the other end of the coil spring is engaged with the lug 25a. The finger piece 27a is movable through the side notch 30a in the flange 18a. The pin 26a normally extends across the slotted opening 36 formed centrally of the plate 19a, the lugs 24a in addition to forming a guide for the sliding frame 28a also cooperating with the upstanding lugs 21a

to provide a space between the top and bottom plates 17a and 19a for the mounting of the sliding pin 26a.

As shown more clearly in Figs. 12 and 13, the base section 16a of the separable button comprises a disk 31a from which a pin 33a centrally rises, the upper end 34a of the pin being flattened for projection through the slotted opening 36 in the bottom plate 19a with the pin 26a received in the opening 35a in the upper end 34a of the pin, the central portion of the top plate 17a being bulged upwardly as at 20a to provide a clearance for the upper end of the pin 33a. The pin 26a is disengaged from the opening 35a in the upper end of the pin 33a upon an outward pull on the finger piece 27a against the tension of the spring 36.

In each form of the invention, the upper end of the pin carried by the base section is shaped to pierce a garment or the like and while there are herein shown and described the preferred embodiments of the invention, it is nevertheless to be understood that minor changes may be made therein without departing from the spirit and scope of the invention as claimed.

I claim:—

1. In a separable button of the character described, head and base sections, a separable interlocking connection between the sections including a pin carried by the base section and resilient means engageable therewith and slidably carried by the head section, the pin having a spear-shaped head defining a base shoulder and the resilient means including a U-shape resilient wire catch having the side legs straddling the pin, and the outer closed end of the catch constituting a finger-piece for slidably disengaging the legs from the pin.

2. In a separable button of the character described, head and base sections, a separable interlocking connection between the sections including a pin carried by the base section and resilient means engageable therewith and slidably carried by the head section, the pin having a spear-shaped head defining a base shoulder and the resilient means including a U-shaped resilient wire catch having the side legs straddling the pin, and said head section being formed of disks with spaced up-set portions carried by one disk for spacing the disks to provide an area for the mounting of the wire catch.

3. In a separable button of the character described, head and base sections, a separable interlocking connection between the sections including a pin carried by the base section and resilient means engageable therewith and slidably carried by the head section, the pin having a spear-shaped head defining a base shoulder and the resilient means including a U-shaped resilient wire catch having the side legs straddling the pin, the outer closed end of the catch constituting a finger-piece for slidably disengaging the legs from the pin, and said head section being formed of disks with spaced up-set portions carried by one disk for spacing the disks to provide an area for the mounting of the wire catch.

JAKOB HOJNOWSKI.
